UNITED STATES PATENT OFFICE.

IRA E. STUMP, OF CLEVELAND, OHIO, ASSIGNOR OF ONE-THIRD TO HERBERT HASTINGS,
OF ROCHESTER, NEW YORK.

ALARM OR SIGNAL APPARATUS.

1,221,920.

Specification of Letters Patent. Patented Apr. 10, 1917.

Application filed May 19, 1914. Serial No. 839,510.

To all whom it may concern:

Be it known that I, IRA E. STUMP, a citizen of the United States, residing at Cleveland, in the county of Cuyahoga and State 5 of Ohio, have invented certain new and useful Improvements in Alarm or Signaling Apparatus, of which the following is a specification.

My invention relates to improvements in 10 alarm or signaling apparatus, and is particularly designed and adapted for use in connection with self-propelled vehicle, such as automobiles, motor trucks, and the like, where an air cooling fan is employed at the 15 rear of the radiator and in front of the engine or motor cylinders for directing currents of air over the latter for cooling the same.

The improved alarm or signaling apparatus 20 is particularly designed for use in connection with or as a part of such air cooling fan in giving the requisite alarm or signal.

The primary object of the invention is to 25 provide a generally improved alarm or signaling apparatus of exceedingly simple, cheap, and efficient construction, the improved apparatus including a centrally located diaphragm suitably mounted within the hub portion of the fan and adapted to be 30 carried by the latter while being rotated.

With the above mentioned, and other ends 35 in view, the invention consists in the novel construction, arrangement, and combination of parts, hereinafter described, illustrated in one of its embodiments in the accompanying drawings, and particularly pointed out in the appended claims.

Referring to the drawings, forming a part 40 of this specification, Figure 1, is a front elevation of an air cooling fan embodying my improved signaling apparatus, a portion of the walls of the fan blades and hub being broken away for the purpose of clearer illustration of the parts.

Fig. 2 is a central sectional view taken on 45 line 2—2 of Fig. 1.

Similar numerals of reference designate like parts throughout all the figures of the drawings.

The improved alarm or signaling apparatus 50 comprises a fan consisting, in the present instance, of a hollow drum or hub portion 1, and a plurality of radially extending tubular fan blades or arms 2, said tubular fan blades being flattened and suitably inclined

as shown most clearly in Fig. 2 of the drawings.

The improved fan is adapted to be mounted at the rear of the automobile radiator and in front of the engine cylinders in the usual 60 manner by means of an attaching bracket 3, provided with suitable bearing members 4, the latter supporting a stub or hub driving shaft 5, said driving shaft being adapted to receive its motion through the medium of a 65 suitable pulley 6, which may receive its motion through a suitable belting or sprocket chain (not shown) communicating with a suitable source of power.

As a suitable source of sound, a sound dia- 70 phragm 7, is provided, said diaphragm 7, in the present instance, being of circular or disk shape and preferably being provided on the one side with a circular series of corrugations or projections 7^a, which latter may 75 be pressed out or formed integral with the diaphragm 7.

As a suitable means of mounting the dia- 80 phragm truss rods 8, are provided said rods being preferably provided with hooked heads 8^a, passing through suitable openings near the outer periphery of the disk shaped diaphragm and being threaded at their outer ends for connection to and adjustment by threaded sleeve screws 9, which latter may 85 be mounted in and supported by suitable cross bars or members 10, extending across the open ends of the flattened tubular shaped fan blades 2.

It will be observed that the tubular fan 90 blades are adapted to act as sound conducting elements for the transmission of the sound waves from the diaphragm when the latter is thrown into motion or vibration by the mechanism hereinafter described.

As a means of vibrating the diaphragm 7, as revolved and carried by the rotating fan a pin or shaft 11, is mounted in the hub driving shaft 5, said pin being adapted to be moved longitudinally within the shaft 5, 100 and against the resistance of a spring 12, through the medium of a suitable cord or actuating device (not shown) connected to the loop head 11^a, and as a means for preventing the circumferential movement of the pin or bar 11, the latter is provided with a groove 11^b, adapted to receive and contain the end of a bracket 3^a, extending upwardly from the stationary attaching bracket 3.

The outer end of the slidably mounted 110

pin or shaft 11, is provided with an arm 13, extending upwardly and carrying a roller head 14, which latter is adapted to be drawn toward and to strike against the corrugations or projections 7^a, of the diaphragm to vibrate the latter when the pin or shaft 11, is drawn rearwardly against the resistance of the spring 12, in an obvious manner by the attached operating mechanism hereinbefore referred to.

10 From the foregoing description, taken in connection with the accompanying drawings, the operation and advantages of my invention will be readily understood.

15 Having thus described one of the embodiments of my invention, what I claim and desire to secure by Letters Patent, is—

20 1. In a signaling apparatus, a rotatably mounted fan including a hollow hub, a diaphragm suspended within said hub and adapted to be rotated with the latter, diaphragm vibrating mechanism within said hub, and means for movably supporting and operating said diaphragm vibrating mechanism.

25 2. In a signaling apparatus, a fan provided with a hollow hub and a hub driving member, a shaft axially mounted within said hub and hub driving member, diaphragm vibrating mechanism within said hub adapted to be operated by said shaft, and a diaphragm suspended within and adapted to be rotated with said hub.

30 3. In a signaling apparatus, a rotatably mounted fan including a hollow hub carrying fan blades, a diaphragm member suspended within and adapted to be rotated with said hollow hub, a diaphragm vibrating member within said hub, and means for moving one of said members into vibrative relation to the other.

35 4. In a signaling apparatus, a fan comprising a hollow hub portion carrying fan blades, a diaphragm suspended within said hub portion and adapted to be rotated with the latter, a contact member within said hub portion in close proximity to said diaphragm, and means for bringing said diaphragm and contact member into vibrative relation to each other.

40 5. In a signaling apparatus, a fan comprising a hollow hub member carrying fan blades, a diaphragm mounted within said hub and adapted to be rotated with the latter, a contact member within said hub, means for supporting said contact member within said hub and in close proximity to said diaphragm, and means for bringing said diaphragm and contact member into vibrative relation to each other.

45 6. In a signaling apparatus, a fan provided with a driving shaft, a diaphragm suspended at the central portion of said fan and adapted to be rotated with the latter, and a non-rotatable shaft longitudinally

movable within said driving shaft and provided with a contact member in proximity to said diaphragm.

7. In a signaling apparatus, a rotatably mounted hollow hub member carrying tubular shaped open fan blades, a diaphragm within said hub, truss rods connected to said diaphragm and extending through said blades and connected to the outer ends thereof, and a contact member adapted to be moved into and out of contact with said diaphragm.

75 8. A signaling apparatus, comprising a hub provided with a stub driving shaft and carrying a plurality of fan blades, a centrally located diaphragm provided with truss rods connected to the ends of said blades, a non-rotatable shaft mounted in said stub driving shaft and longitudinally movable therein, and a contact member carried by said non-rotatable shaft and adapted upon the movement of the latter to be thrown into and out of engagement with said diaphragm.

80 9. A signaling apparatus, comprising a hollow fan hub carrying open tubular shaped fan blades, a diaphragm within said fan hub and provided with a circular series of projections, truss rods connected to said diaphragm and extending through said fan blades, supporting members connected to the outer ends of said truss rods and said fan blades, a rotatably mounted shaft connected to and carrying said fan hub, a non-rotatably mounted spring-resisted slide mounted within said driving shaft and provided with a contact member adapted to be thrown into and out of engagement with said projections on said diaphragm.

85 10. In a signaling apparatus, a rotatably mounted hollow hub member carrying fan blades, a diaphragm within said hollow hub member, a contact member in proximity to said diaphragm, means for supporting said contact member, and means for bringing said diaphragm and contact member into operative relation to each other.

90 11. In a signaling apparatus, a rotatably mounted hub carrying fan blades, a diaphragm suspended at one side of said hub and adapted to be rotated with the latter, a contact member at one side of said diaphragm, means within said hub for supporting said contact member, and means for causing said contact member to be brought into vibrative relation to said diaphragm.

95 12. In a signal the combination of a revolving pulley, a support therefor, means located centrally of the pulley and revolving therewith for producing sounds proportioned in pitch to the speed of rotation of said pulley, a striking device movable within said support into and out of engagement with said means.

100 13. In a signal the combination of a re-

- volving fan, means located centrally thereof and operated thereby for producing sounds proportioned in pitch to the speed of rotation of said fan, a pulley for driving 5 said fan, a support for said pulley, striking means adjustably mounted within the support to vary the volume of the sound produced thereby at will without interfering with the operation of the fan.
- 10 14. In a signal the combination of a revolving fan, a support therefor, a horn and a diaphragm circumferentially supported in said horn and adapted to rotate with said fan, a projection on said diaphragm, a 15 striker movable within said support into and out of engagement with said projection to cause the vibration of the diaphragm on the rotation thereof while in engagement with said striker.
- 20 15. In a signal, the combination of a revolving horn and diaphragm circumferentially supported therein, a support therefor, a projection on said diaphragm, a striker movable within the support into and out of 25 engagement with said projection to cause the vibration of the diaphragm on the rotation thereof while in engagement with said striker.
16. In a signal the combination of a revolving fan, a support therefor, a member circumferentially supported in said fan for producing sound waves, a device within said support for vibrating said member, the revolution of said fan causing relative movement 30 between the member and the device for vibrating said member for producing sound, one of said parts being manually movable to cause engagement or disengagement between the parts.
- 35 17. In a signal the combination of a revolving fan, an axle, a member for producing sound waves circumferentially supported centrally on said fan and rotating therewith and a device within the axle for vibrating said member.
- 40 18. In a signal the combination of a revolving fan, a support therefor, a member for producing sound waves circumferentially supported centrally on said fan and
- 45
- rotating therewith and a device for vibrat- 50 ing said member, said device being movable within the support into and out of engagement with said member.
19. In a combination, a rotating fan, a support therefor, a vibratile sound produc- 55 ing element normally inoperative and circumferentially supported on said fan for vibration in a direction parallel to the axis of the fan, said element extending parallel to the plane of rotation of the fan and means 60 within the support for vibrating the sound producing element by the rotation of the fan.
20. In a signal, the combination of a stem, a horn mounted to rotate about said stem, a diaphragm circumferentially supported in 65 said horn, a projection on said diaphragm moving therewith, a projection mounted on said stem with which the projection on the diaphragm engages on the rotation thereof.
21. In a signal the combination of a stem, 70 a horn mounted to rotate about said stem, a diaphragm circumferentially supported in said horn, a projection on said diaphragm moving therewith, a projection mounted on said stem with which the projection on the 75 diaphragm engages on the rotation thereof, and means mounted concentrically with said horn for rotating the horn.
22. A sounding device having, in combination, a stud, a fan rotatably supported upon 80 the stud, a diaphragm secured to the fan, and an actuating member slidingly supported in the stud and arranged to be moved into operative relation with the diaphragm to positively vibrate the diaphragm. 85
23. A sounding device comprising a fan having a hub, a diaphragm secured in the hub, an actuating member sliding in the hub, and means under the control of the operator for moving the actuating member into and 90 out of engagement with the diaphragm.

In testimony whereof I have affixed my signature in presence of two witnesses.

IRA E. STUMP.
